UNITED STATES PATENT OFFICE.

ERNEST M. ROSE, OF DULCE, NEW MEXICO, ASSIGNOR OF ONE-HALF TO CHARLES H. McCORMICK, OF DULCE, NEW MEXICO.

NAILING FRAME.

Application filed March 11, 1924. Serial No. 698,483.

To all whom it may concern:

Be it known that I, ERNEST M. ROSE, a citizen of the United States residing at Dulce, in the county of Rio Arriba and State 5 of New Mexico, have invented certain new and useful Improvements in Nailing Frames, of which the following is a specification.

This invention relates to improvements 10 in nailing frames, and particularly to a frame for holding angular corner pieces of boxes, while the end pieces are nailed thereto.

An object of the invention is to provide 15 a pair of angle bars of suitable form for receiving the angular corner pieces adapted to secure the side and end pieces in crate forming relation, and for strengthening the corners of the crate.

20 This invention is used in connection with crates which are formed of a plurality of spaced side and end members to provide a crate suitable for shipping fruit, such as pineapples and the like, the end pieces used 25 being of triangular cross section, which occasions difficulty in the assemblage of the corner pieces and the nailing of the end and side pieces thereto, as it is difficult to hold these triangular corner pieces in position, while the side and end pieces are 30 nailed thereto. This invention, therefore, provides a frame which is adapted to hold these corner pieces while the end pieces are nailed thereto, in order to prevent the same 35 from becoming twisted and out of alignment, which will make it difficult to assemble the crate, this invention holding corresponding sides of the triangular corner post in proper relation, until the end pieces are 40 nailed thereto.

45 A further object of the invention is to provide a plurality of spacing members adjustably mounted on the angular end bar, which receives the corner post, and are held in spaced relation by suitable side members connected thereto for accurately positioning the end pieces or boards in proper spaced relation.

50 The invention includes other objects and 55 improvements in the details of construction, and arrangement of parts, which are more particularly pointed out in the following description and claims, directed to a preferred form of the invention, it being understood, however, that variations may be

made, within the scope of the invention, as described and claimed.

In the drawing, forming a part of the application:

Figure 1 is a plan view of the invention, 60 showing the corner posts in position in the anchor members, and the end pieces nailed thereto.

Figure 2 is a sectional view, taken on the line 2--2 of Figure 1. 65

Figure 3 is a detail perspective view, of one of the positioning plates adjustably mounted on the angle member.

Figure 4 is a plan view of the invention, 70 with the corner post and end pieces removed.

Fig. 5 is a sectional view, taken on the line 5--5 of Figure 4.

The angle members, which are of duplicate form, are indicated at 1, and are of a 75 cross section as indicated at Figure 2, having a vertical wall 2, and an angular wall formed integral with the vertical wall 2, and extending at an angle of substantially 45° in relation to said vertical wall as indicated at 3, said angular wall being formed with a plurality of aligned openings 4, for a purpose to be presently described. The ends of the angular wall 3 of the members 1, are formed with laterally extending flanges 5, arranged in a substantially vertical plane, and the vertical walls 2 are formed with flanges 6 beyond the flanges 5, and in spaced relation therewith, as clearly shown in Figure 4, for receiving between the flanges 5 and 6, the side bars 7, which are formed with an arcuate recess 8, in the central portion, and are adapted to be secured to the flanges 5 and 6, by suitable rivets 9 or the like, for holding the angle members 1 in 95 rigid spaced relation. The angle members are joined, in the central portion, by a central bar member 10, having the end portions thereof inclined relative to the body of the bar, and secured to the angular walls 3 of 100 each member, for preventing flexing of the central portion of the member.

Spacing members are indicated at 11 and 105 12 respectively, each being formed of plates 13, having a longitudinally extending slot 14, and a lateral flange 15, on the upper edge thereof, adapted to engage the upper edge of the angular wall 3, the spacing members 11 being formed at one end with 110 upwardly extending fingers 16, adapted to

project above the upper end of the angular wall 3, while the spacing members 12 are formed at the opposite end of the plates 18, with corresponding fingers 17, also extending above the upper free edge of the angular wall 3, the purpose of these spacing members being to position the end pieces, which form the end of the crate, in proper relation on the corner posts. This functioning of the spacing members is indicated clearly in Figure 1, where the corner posts are shown, at 18, seated in the angle members 1, and on the upper faces of which are nailed the end pieces 19, the spacing members in this case, being used, to properly position the central end piece, in the central portion of the corner post 18, in order to provide equal faces at each side of the central piece and the upper and lower end pieces, the edges of which terminate at the ends of the corner posts. Suitable bolts, having wing nuts, extend through the openings 4, in the angular walls 3 of the members 1, and the slots 14, of the spacing members, as clearly indicated at 20, for securing the members to the angle members, and permitting the adjusting thereof, for spacing the end pieces in proper relation, on the corner post.

With the use of this nailing frame, it will be clear from the above description, that the corner posts, of triangular section, used in the formation of fruit crates, and the like, when positioned in the angle members 1, will be retained therein, in such a position that the end pieces of the crate may be conveniently nailed thereto, without the danger of having the pieces becoming twisted during the nailing operation, so that a true and uniform box structure will result, as well as facilitating the ready nailing of the end pieces to the corner posts. The arcuate recesses 8 in the side bars, are provided for the insertion of the fingers, so that the assembled ends of the crate may be easily removed from the nailing frame. It is to be understood, in this connection, that the frame may be provided in a desired size, in order that boxes of

various sizes may be quickly and easily assembled.

What is claimed is:

1. A nailing frame for crates, including a pair of angle members formed with vertical walls, and integral angle walls extending therefrom, each of said walls being formed with laterally extending flanges arranged in spaced parallel relation, side members having the end portions inserted between the spaced flanges of said angle member and secured thereto, for holding said angle members in spaced parallel relation, a central spacing bar secured to the angle wall of said angle member, and a plurality of spacing members removably and adjustably mounted on the angular walls of said angle member adapted for positioning end pieces in spaced relation on said frame, said angle members being adapted to receive corner posts of substantially triangular cross section for positioning corresponding faces thereof in position to receive end pieces to be nailed thereto.

2. A nailing form for an end frame, such as is used in the make up of a shipping crate, said form comprising a pair of duplicate post receiving members, each member being substantially V-shaped in cross section and being open at its opposite ends, the side walls of the member being fashioned at the end to provide angularly directed flanges, the adjacent ones of which are spaced apart, a pair of connecting strips having their opposite ends disposed between the pairs of flanges provided at the opposite ends of said members and connecting said members together and closing the ends of the same, a pair of spacing clips for each member, said clips being adjustably mounted on the inner walls of the members and being provided with upstanding fingers between which a portion of the end frame of the crate is adapted to be confined, and means connecting said clips with said members.

In testimony whereof I affix my signature.

ERNEST M. ROSE.
